(57) **CLAIM**

The ornamental design for a reader device, as shown and described.

DESCRIPTION

FIG. 1 is a front perspective view of a reader device showing our new design;

FIG. 2 is a top plan view thereof;

FIG. 3 is a left elevation view thereof;

FIG. 4 is a right elevation view thereof;

FIG. 5 is a rear elevation view thereof; and,

FIG. 6 is a front elevation view thereof.

The broken lines illustrate environment and are included for the purpose of illustrating unclaimed features of the design.
